J. T. L. Wright

WITNESS:

Benjamin F. Mills INVENTOR
BY *Victor J. Evans* ATTORNEY

UNITED STATES PATENT OFFICE.

BENJAMIN F. MILLS, OF SIOUX CITY, IOWA.

OIL BURNER.

Application filed November 14, 1923. Serial No. 674,730.

To all whom it may concern:

Be it known that I, BENJAMIN F. MILLS, a citizen of the United States, residing at Sioux City, in the county of Woodbury and 5 State of Iowa, have invented new and useful Improvements in Oil Burners, of which the following is a specification.

This invention relates to liquid fuel burners, and has for its object the provision of a 10 novel burner for utilizing oil as a fuel, the burner being adapted for use in connection with heating or cooking stoves, heating plants, steam generators and the like, there being no restriction whatever as to the field 15 of utility or the size which may naturally be varied to suit the requirements of the service desired.

An important object is the provision of a 20 burner which is provided with priming means for initially heating the fuel to effect vaporization thereof so that it will be easily combustible, means being also provided for supplying the proper admixture of air to insure thorough combustion.

An additional object is the provision of a 25 device of this character which will be simple and inexpensive to manufacture, easy to install, positive in action, efficient and durable in service and a general improvement 30 in the art.

With the above and other objects and advantages in view the invention consists in the details of construction to be hereinafter more fully described and claimed and illustrated in the accompanying drawings, in 35 which:

Figure 1 is a side elevation of the device showing it embedded within an ash pit,

Figure 2 is a longitudinal section through 40 the device alone in slightly spaced relation thereto,

Figure 3 is a plan view of the burner with the top element thereof removed.

Referring more particularly to the drawings the numeral 10 designates a fuel conducting pipe upon the upper end of which is mounted my burner structure which includes a disk 11 having a hub 12 surrounding a central threaded bore 13 which is screwed onto the pipe 10. This disk has an upstanding peripheral flange 14 so as to hold a small quantity of oil and to serve as a priming pan. Above the disk 11 is the burner proper which comprises a disk 15 having a hub 16 formed with a threaded recess 17 screwed onto the upper end of the

pipe 10. At its center the disk is provided with a small hole 18 which communicates with the recess therein and which is for the outlet of fuel. The top surface of the disk 15 is formed with a plurality of concentric grooves 19 so as to increase the active surface to the maximum. The burner further includes an upper disk 20 which fits upon the disk 15 and which is held thereon by a plurality of lugs 21 formed upon the disk 20 and projecting over the edge of the disk 15. This upper disk 20 is concaved on its underside so as to define a space 22 above the top surface of the disk 15.

The device is intended to be mounted within the ash pit of a stove, furnace or the like or upon the grate but in any event I provide a cylindrical sleeve 23 which is disposed about the pipe below the disk 11 and which is embedded for the greater portion of its height in a mass 24 of ashes or the like so as to prevent air from entering at any place other than through openings 25 at the upper edge of the sleeve.

Assuming that the device has been constructed, assembled and installed as above indicated, it will be apparent that to effect starting, a certain amount of oil is poured into or allowed to flow onto the disk 11 which constitutes the priming pan and this oil is ignited so that it will burn and heat the entire device very thoroughly. When the oil is then turned on it will issue from the hole 18 and flow onto the disk 15 which has been heated by the flame rising from the priming pan and this heat will operate to vaporize the oil so that it will issue from the slight space between the disks 15 and 20 and burn to produce a sheet like flame. The air entering through the openings 25 gives the proper amount of oxygen to insure proper combustion.

From the foregoing description and a study of the drawings it will be apparent that I have thus provided a simple, inexpensive and easily installed burner which will be highly efficient for the purpose specified and also for all kindred and analogous purposes and which on account of its simplicity and fewness of parts is not likely to get out of order.

While I have shown and described the preferred embodiment of my invention it is of course to be understood that I reserve the right to make such changes in the form, construction and arrangement of parts as

will not depart from the spirit of the invention or the scope of the subjoined claim.

Having thus described my invention I claim:

6. A burner comprising a pipe adapted to have fuel pass therethrough, a priming pan screwed onto the pipe, a disk carried by the pipe above the priming pan and having a central hole communicating with the pipe,

the top surface of said disk being formed 10 with concentric grooves for increasing the area and providing oil retaining means, a dished inverted disk mounted above the first named disk, and a sleeve beneath the priming pan having its upper edge formed with 15 openings for the inlet of air.

In testimony whereof I affix my signature.

BENJAMIN F. MILLS.
